UNITED STATES PATENT OFFICE

161,856

SLIDE VIEWER

John R. Miles, Chicago, Ill., assignor to
Michael S. Wolk, Chicago, Ill.

Application September 15, 1950, Serial No. 12,198

Term of patent 14 years

(Cl. D61—1)

To all whom it may concern:

Be it known that I, John R. Miles, a citizen of the United States, and resident of the city of Chicago, county of Cook, and State of Illinois, have invented a new, original, and ornamental Design for a Slide Viewer, of which the following is a specification, reference being had to the accompanying drawing forming a part thereof.

Fig. 1 is a perspective view of a slide viewer, showing my new design.

Fig. 2 is a perspective view thereof, showing the back and one side thereof.

Fig. 3 is a side view thereof.

Fig. 4 is a top view thereof.

I claim:

The ornamental design for a slide viewer, substantially as shown.

JOHN R. MILES.
